United States Patent

Des. 240,037
Patented May 25, 1976

240,037

GATE VALVE BODY

Willard E. Kemp, Houston, and Wayne B. Palmer, Richmond, Tex., assignors to ACF Industries, Incorporated, New York, N.Y.

Filed Jan. 23, 1975, Ser. No. 543,205

Term of patent 14 years

Int. Cl. D23—01

U.S. Cl. D23—19

FIG. 1

FIG. 2

FIG. 3FIG. 4FIG. 5FIG. 1 is a perspective view taken from the front and top of a gate valve body showing our new design;

FIG. 2 is another perspective view taken from the front and one end thereof;

FIG. 3 is a top plan view thereof;

FIG. 4 is a bottom plan view thereof; and

FIG. 5 is a third perspective view taken from the rear and one end thereof.

We claim:

The ornamental design for a gate valve body, as shown.
